UNITED STATES PATENT OFFICE.

FERDINAND KRONENBERGER, OF NEW YORK, N. Y., ASSIGNOR TO FREDERIC B. CLARK,
OF ENGLEWOOD, NEW JERSEY.

EGG-CONTAINER.

1,209,649.

Specification of Letters Patent. Patented Dec. 19, 1916.

Application filed March 8, 1913. Serial No. 752,811.

To all whom it may concern:

Be it known that I, FERDINAND KRONENBERGER, a citizen of the United States, residing in the city of New York, borough of Queens, county of Queens, and State of New York, have invented a certain new and useful Egg-Container, of which the following is a specification.

This invention pertains to egg crates, and the object of the invention is to enable eggs to be packed and shipped, particularly by parcel post, without danger of breakage.

It is well known that an egg is capable of withstanding very considerable pressure provided the line of stress is in the direction of the longitudinal axis of the egg. My purpose is to utilize this capacity of eggs so that they may be shipped and handled with very little, if any, liability to breakage. Accordingly, the invention embodies a plurality of members between which a layer of eggs is positioned in such manner that the respective end portions of the eggs are in frictional contact with said members, but a salient feature of the invention is that means are provided for clamping said members upon or against the end portions of the eggs composing the layer whereby some considerable pressure is applied to the eggs, the line of such pressure or stress being in the direction of the length of the eggs. The eggs are thus retained securely between the members so that they cannot move loosely and break when the package is handled roughly, and at the same time the eggs are held in such manner, to wit, under pressure applied in the direction of the greatest resistance of their shells, that the eggs themselves are not liable to become broken even though the package itself should become damaged during transportation.

In the accompanying drawings I have illustrated different practical embodiments of the invention, but the constructions shown therein are to be understood as illustrative only, and not as defining the limits of the invention.

Figure 1 is a transverse section through an egg carrier embodying the preferred form of my invention. Fig. 2 is a fragmental plan thereof, the cover of the receptacle, in which the egg carrying unit is positioned, being removed. Fig. 3 is a longitudinal section of a certain tie bar which

may be employed to hold the clamping members of the egg carrier in fixed position relative to one another. Figs. 4; 5; 6, 7, and 8; and 9 and 10 are views illustrating modified forms of the invention. Fig. 11 is a detail of a modified self-locking tie bar which I sometimes prefer to employ. Fig. 12 is a partial plan view of the clamping plate in another embodiment of the present invention, and Figs. 13 and 14 are a fragmental plan and transverse section of a further embodiment thereof.

In said drawings, and particularly in Figs. 1 and 2, A designates a container or receptacle having a suitable cover B. C and D denote two complementary gripping plates. These gripping members, C, D, are formed with depressions c, d, respectively, and are practically the same in all essential particulars.

Tie bars E are provided for the purpose of forcing the plates toward one another so that they will tightly grip the opposite ends of eggs which have been previously positioned with their ends in the aforesaid depressions c, d. In Fig. 3, a detail of the tie bars delineated in Figs. 1 and 2, is shown. For a detachable connection, this tie is admirably adapted to this use, as its head enclosing member e, and nut portion e', form points of support for the egg holding unit within its receptacle or container. In Fig. 1, where a single unit is shown as contained in a container, these points of support obviate any chance of the clamping plates coming into contact with the top or bottom of said container, which would be apt to result in the breakage of the eggs. It is obvious that a plurality of units may be contained, on top of one another in the same receptacle, in which case these supporting points will keep the adjacent units from contacting with one another. It will be understood, however, that, while the aforesaid tie bar performs its functions with high efficiency, a threaded rod with nuts, an ordinary bolt, or any other equivalent means may be employed; e. g., see Fig. 5.

In practice, the eggs are set on end in their individual seats d, in the bottom plate D, the top plate C is then placed in juxtaposition over the bottom member, and the tie bars are then put in place and tightened to exert pressure on the plates and cause them to grip the eggs. The difference in

size of the eggs is compensated for by the resiliency of the plates, and this is augmented by cutting away portions thereof, as at c' , d' , thereby allowing the different portions of said plate to better adapt themselves to the sizes of the eggs. The present invention is, however, not limited to the use of tie bars for exerting pressure at or near the ends of the eggs. In Fig. 4, a construction is shown, wherein egg gripping members F, G, formed with depressed seats for the individual reception of eggs, are provided around their peripheries with upturned flanges, f and g , respectively, which extend at right angles to the planes of their respective members. The gripping plates, thus formed, are so placed in the closure or receptacle A', in which they are to be shipped, that the flange g , of bottom gripping member G, will rest on the bottom of said receptacle, and, when the eggs are in proper position in their individual seats in the top and bottom members, the flange f , of the top member, will project slightly above the top of the box. It is thus obvious that, when the cover B' is forced down and secured in place, it will, in turn, exert force on the flange f of the upper plate, which, being somewhat resilient, will simultaneously place all the eggs in the unit under pressure.

It will be noted that, in Figs. 4 and 5, the crowns of the depressed egg seats c' , d' , are cut out so that eggs are gripped over the arches at their opposite ends. This gripping over the arch is a modification of my invention, and it will be understood that, in the various constructions illustrated in the drawings, the individual egg seats may have either solid or apertured crowns.

A modified form or application of my invention is disclosed in Figs. 6 and 7, in which the blanks, from which two complementary clamping members, H and I, (upper and lower, respectively) are formed, are shown. Each of these blanks comprise a central longitudinal portion running the complete length thereof, and forming the backbone of the blank, and a plurality of laterally extending tongues, h , i , near the end of which, and in alinement with one another, are provided depressed seats h' , i' . The tongues on either side of the backbone are alternately long and short on one side thereof, and vice versa on the other side. Moreover, the portion J of each of the longer tongues, which extends beyond the shorter ones, is adapted to be bent up, as on the dotted line j , whereby an intermittent flange is formed along both longitudinal edges of each of the clamping members H, I. It will, moreover, be understood that the flange on the upper clamping member, H, extends upwardly therefrom, and that the flange on the lower

clamping member, I, extends downwardly therefrom.

In use, the eggs to be carried are adapted to be placed on end in the depressed seats h' , i' of the upper and lower members H, 70 and I, respectively, and said members are then forced together by suitable means, such as the tie bars K, which extend through the apertures k , k' , in the backbones of said members. Fig. 8 shows a single unit of the 75 type just described, illustrating how, when packed in a receptacle, the intermittent flanges preclude the rattling of the unit within its receptacle, which would result in breakage of the eggs.

The material from which the clamping members are stamped, is quite thin so as to be as light as possible, and the requisite strength and stiffness are preferably provided by corrugating said members transversely thereof, between each pair of egg seats, as at h^2 , i^2 .

Aside from the function of adding stiffness to the clamping members, the corrugations have an important additional function, in providing a non-refillable unit. It is obvious that, if the tie bar K, is made self-locking, e. g., as shown in Figs. 8 and 11, it would be impossible to loosen it and remove the eggs, and it would, consequently, 95 be necessary to bend up each individual tongue and remove the eggs separately. Manifestly, however, when bending up the tongues, it is necessary to break, or, at least, greatly disfigure, the corrugations, thus 100 rendering the clamping member unfit for further use.

Figs. 9 and 10 illustrate another embodiment of the invention, the latter figure showing a part of one of the clamping members O, in side elevation, and the former figure showing a number of these sections assembled and held in such position by a plurality of tie bars P. As clearly shown, each of these sections O is stamped from sheet 105 metal, paper, fiber, or the like, and is transversely slotted between each pair of egg seats o as at o' , a little over a third of its width and from each longitudinal edge. This slotting of the clamping sections enhances the resiliency thereof, allows for the accommodation of the varying sizes of eggs, and, if self-locking tie bars such as the bar P, are employed, permits the eggs to be removed 110 separately, as in the construction illustrated 115 in Figs. 6, 7 and 8. Moreover, if it is desired to make the carrier non-refillable, the sections may be corrugated as in said modified form of Figs. 6, 7 ad 8.

The blanks, from which these sections O 125 are made, are sufficiently wide to allow their lateral edges to be formed into interlocking male and female flanges q , q' , respectively, whereby a plurality of these sections may be placed, one on top of the other, to accommo- 130

date any desired number of eggs, and then secured together and placed under pressure by the tie bars P.

In Figs. 8, 9 and 11, I have illustrated one practical embodiment of a self-locking tie bar adapted to be used in connection with my invention. The head p, and its shank p', of this bar P, may be stamped from sheet metal, fiber, or the like, and is provided for 10 a portion of its length with notches p², along its edges. A securing member R, which may be also stamped from like material, embodies, figuratively speaking, a tapered split sleeve r, having a retaining flange r', around its large end. This securing member may, by virtue of the slit r² therein, be forced over the shank of the tie bar, it being manifest that, when the smaller end of the sleeve comes into juxtaposition with 20 the notches p², said sleeve will spring shut, thus precluding the withdrawal of the securing member.

In Fig. 12, a further modification of the invention is shown. In this figure, a number 25 of tongues s, are stamped from the clamping plates, each tongue being provided with an egg seat s'. It will be understood that a unit of this embodiment embodies two complementary plates, which are clamped together by a tie bar S', as will be readily understood. The tongues, above referred to, being quite resilient, compensate for the varying sizes of different eggs. Moreover, if a non-refillable unit is desired, the self-locking tie bar, illustrated in Fig. 11 of the drawings, may be employed, in which case, it will be impossible to remove the eggs from the unit without bending up the tongues s, as indicated by the dotted lines s². This bending up of the tongues will take away their resiliency and render the unit valueless for further use.

Figs. 13 and 14 illustrate a construction 45 very well adapted for the carrying of different size eggs. This construction embodies a pair of clamping plates T, T', which may be clamped together, and retained under pressure by any tie bar t, hereinbefore described. Said plates are provided with oppositely positioned egg seats t', the crowns of which are cut out, preferably in star form, to provide an egg seat embodying a series of resilient tongues adapted to engage the egg near the end thereof. It will 50 thus be obvious that, when different size eggs are placed in the same unit, and pressure applied through the tie bar t, the resiliency of the tongues t' will allow the large eggs to extend farther into their seats than the smaller eggs, all as clearly shown in Fig. 14. Consequently, the clamping plates T, T', will be always in parallel relation, and will 55 readily grip eggs of varying sizes, with equal efficiency.

60 It will be understood that, while I have

shown several embodiments of the present invention, and while each embodiment may have its distinctive feature or features, I do not wish to be understood as limiting these features to the specific embodiment in which 70 they happen to be shown, but that many are interchangeable between the several embodiments; e. g., it will be obvious that the type of egg seat, shown in Fig. 13, could be readily used in the embodiment of the invention shown in Fig. 12, and the egg seat with the closed crown, as shown in Fig. 1, could be readily embodied in the construction shown in Fig. 4, while almost any one of the egg seats shown might be employed 80 in the construction illustrated in Fig. 9. I, therefore, do not wish to be understood as limiting these specific features to the embodiments in which they are shown.

In all the embodiments of the invention 85 herein shown and described, it will be obvious that, since the pressure applied is positive, the eggs are held sufficiently tight to preclude their disengagement from their seats, under the most trying conditions. 90 Consequently, it is immaterial on which side the container is set down, as the eggs cannot work or jar loose, and, at the same time, sufficient resiliency is inherent in the construction and material employed to pre- 95 clude any fear of breakage.

Having thus fully described the invention, what I claim as new, and desire to secure by Letters Patent is:—

1. An egg carrier embodying a plurality 100 of substantially rigid egg gripping sheets positioned one over the other, said sheets having direct frictional engagement with rows of eggs at the extreme ends thereof, and means whereby said gripping sheets are 105 movable relatively to each other for securing pressure upon the extreme ends of the eggs.

2. An egg carrier embodying a plurality 110 of substantially rigid egg gripping sheets positioned one above the other, said sheets having direct frictional engagement with rows of eggs at the extreme ends thereof, and means whereby said gripping sheets are moved relatively to each other and thereby brought forcibly into contact with all the 115 eggs so as to apply pressure upon the extreme ends of the eggs through the medium of the sheets themselves, the line of direction of such pressure being lengthwise of the eggs.

3. An egg carrier embodying a plurality 120 of substantially rigid egg gripping sheets positioned one above the other, said sheets having depressions integral therewith and positioned for direct frictional engagement 125 with rows of eggs at the extreme ends thereof, and means for bodily moving the sheets so as to force the depressions thereof toward the eggs positioned between them, whereby positive pressure is applied to the 130

eggs at the extreme ends thereof through the medium of the sheets themselves, the line of such pressure being in the direction of the longitudinal axis of the eggs.

- 5 4. An egg carrier embodying substantially rigid plates having rows of pockets integral therewith and positioned for direct frictional contact with rows of eggs at the respective end portions thereof, and means for bodily moving said plates so as to forcibly engage with the end portions of the eggs whereby pressure is applied upon the extreme ends of the eggs and in the direction of their longitudinal axes.
- 15 5. An egg carrier embodying substantially rigid gripping plates having rows of pockets integral therewith and positioned for direct frictional engagement with the eggs at their ends, and tie bars connected to said gripping plates for forcibly applying pressure upon the extreme ends of the eggs by the contact therewith of said pockets.
- 25 6. In an egg carrier, the combination of a plurality of substantially rigid plates provided with tongues forming seats integral with said plates and positioned for direct frictional contact with the eggs, and means for forcibly applying pressure to said plates whereby pressure is exerted upon the extreme ends of the eggs through said tongues of the members.
- 35 7. In an article carrier, the combination of a plurality of substantially rigid gripping plates positioned in opposing relation for receiving rows of articles to be gripped between them, said plates being provided in their opposing faces with rows of seats for direct frictional contact with the respective end portions of said articles, and pressure means coöoperating with said plates for ef-

fecting relative movement between them so that the seats of the plates will apply pressure to the extreme end portions of the articles, the direction of the pressure so applied being lengthwise of the articles 45 gripped between the plates.

8. An article carrier embodying a plurality of substantially rigid members provided with means for nesting them relatively to each other, said members being positioned in 50 opposing relation to each other and provided in their opposing faces with rows of seats for direct frictional engagement with the respective end portions of the articles adapted to be positioned between said members, and means for applying pressure to the members so that pressure will be applied through the seat portions thereof to the extreme end portions of the articles retained between the members, the direction of pressure so applied being lengthwise of the articles 55 positioned intermediate said members.

9. A shipping case for eggs comprising a rigid retaining means for the eggs, and means for securing pressure upon the extreme ends of the eggs for the purposes set forth.

10. A shipping case for eggs comprising a rigid retaining means for the eggs, and means for securing pressure upon the extreme ends of the eggs for the purposes set forth, the pressure being applied in the direction of the longitudinal axes of the eggs.

In testimony whereof I have signed my name to this specification in the presence of 75 two subscribing witnesses.

FERDINAND KRONENBERGER.
